ABSTRACT OF THE DISCLOSURE

A hydraulic control device for simultaneously locking or unlocking several panels or doors of vehicles, characterized by a manual control device having a push-button and toothed-rod acting on a piston supported on a deformable diaphragm mounted inside a cylinder connected to a hydraulic conduit terminating in receiving bolt devices, while an automatic control comprising a regulator driven from the gear-box, displaces a piston acting on a deformable diaphragm of a chamber coupled to the conduit of the manual control device.

The present invention relates to a hydraulic device for simultaneously locking several panels or doors of vehicles, providing a safety device, at the same time against opening of the said panels or doors when the vehicle is running and against their undesired locking in the event of accident.

The device forming the object of the invention comprises means for controlling the locking of the panels or doors when the vehicle is stopped, especially key controls for the exterior on leaving the vehicle, and push-button controls for the interior when it is desired to ensure its safety when stopped, and means for controlling automatically the locking of these panels or doors when the vehicle is travelling above a certain speed and the suppression of this locking action below the said speed, which furthermore provides a safety device for children, and safety against any risk of being locked inside the vehicle in case of accident.

Other characteristic features of the device according to the invention will be brought out in the description which follows below, by way of example and without any limitation, reference being made to the accompanying drawings, in which:

FIG. 1 shows diagrammatically the general arrangement of the device in the unlocked position;

FIG. 2 is a view in cross-section taken along the line II—II of FIG. 1;

FIG. 3 is a view of a detail;

FIG. 4 represents the general arrangement of the device in the locked position;

FIG. 5 is a view in cross-section taken along the line V—V of FIG. 4.

Referring now to FIG. 1, it can be seen that this device comprises essentially a manual interior control member 1, an automatic control member 2 controlled by a regulator 3 taking its drive from the gear box, receivers 4 with bolts 9, and two external control key members, one on the right-hand side 5D and the other on the left 5G. A hydraulic circuit H couples together the control members 1 and 2 and the receivers 4.

The control member 1 comprises a push-button 10, the toothed-rack shaft 13 of which controls the piston 7 acting on the deformable diaphragm 6 inserted in the cylinder of the member 1. The toothed rod 13 is provided with a cavity 12 and a ball 11 is housed in a guide 11¹ rigidly fixed to the cylinder of the member 1, the ball

being subjected to the action of a spring 14 and coming into engagement with the cavity 12 during the movement of the rod 13.

The toothed rod 13 is associated with a pinion 20 rotatably mounted on the shaft 21 and having no effect on the external control devices 5D—5G. Each of the devices 5D and 5G comprises a barrel of known type with alternative movement to the right or to the left, having the purpose of actuating the pinion 20 and the toothed shaft 13 by means of an extension 22 coupled on the one hand to the nose of the barrel and on the other hand to a part 23 or 24, independent of each other, but operating through a dog 25 or 26 the pinion 20 which is in turn provided with two projections 27 or 28.

The automatic control device comprises the regulator 3, taking its drive from the gear-box of the vehicle, acting on the suitably-guided rod of the piston 15 which is supported on the deformable diaphragm 29, inset inside the cylinder of the device 2.

The bolts 9 of the receiver 4 previously indicated, comprise a rod rigidly fixed to a piston bolt 9 supported on the deformable diaphragm 30, the piston being subjected to the action of a spring 18.

The device for simultaneously locking the panels or doors operates in the following manner:

If action is taken on the push-rod 10 of the manual internal control device 1, the rod 13 drives the piston 7 supported on the diaphragm 6, displaces the volume of liquid 8 towards the receiver 4 (the displacement towards the device 2 not being operative due to the position of the piston 15, at 16), the bolts 9 of which move into their locking position (see FIG. 4); this movement can be generated either by the push-button 10 of the control device 1 or from either side of the vehicle by the key controls 5D—5G which operate the pinion 20 and the toothed rod 13, following the arrangement previously described. The locked position is retained by the ball 11 which becomes housed inside the cavity 12 of the toothed rod 13 by the action of the pressure spring 14. The force of the ball 11 must compensate for the forces of the pressure springs 18 contained in the receivers.

Starting from this position, if the vehicle is put into movement, the automatic control device 2 comes into operation and is modified by the action of the regulator 3, and the piston 15 takes up the position indicated at 16, while the piston 7 of the device 1, which was in the position 17, returns to 7 and the bolts 9 remain in the position shown in FIG. 4.

When the vehicle stops, the piston 15 of the device 2 returns from the position 16 to its initial position by the action of the regulator 3 and the total volume of the receivers 4 returns to 19, aided by the springs 18 of the bolts 9, which have a dual purpose:

- (1) To activate the circulation,
- (2) To permit uniform deformation of all the diaphragms 6—29—30.

In this condition, the bolts 9 have returned to their original non-locked state as shown in FIG. 1.

It will be noted that, irrespective of the position of the toothed-rod 13, that is to say locked or not locked, the control by the devices 4D—5G can be effected and gives the bolt devices a position inverse with respect to the first condition, which permits unlocking from the side opposite to that at which the locking has been effected and conversely.

I claim:

1. A hydraulic control device for simultaneously locking or unlocking a plurality of panels or doors of vehicles, providing at the same time a safety device against the opening of said panels or doors when the vehicle is running and against their undesired locking in the case

of an accident, a bolt for each panel or door, a manual control device comprising a push-button with a toothed-rod acting on a piston supported by a deformable diaphragm mounted inside a cylinder connected to a hydraulic conduit which terminates at receiver devices which actuate the locking bolts, an automatic control comprising a regulator adapted to be driven from the gear-box of the vehicle, said regulator displacing a piston supported on a deformable diaphragm within a chamber coupled to the conduit of the manual control device which terminates at the receiver devices controlling the locking bolts.

2. A hydraulic control device in accordance with claim 1, in which the manual control device with a push-button and toothed-rod is associated with external key devices on right-hand and left-hand sides thereof and acting independently of each other on a pinion engaging with the toothed-rod of the bush-button of the manual control device, said manual control device having a locked position which is adapted to be maintained by a

spring ball locking device engaging in a cavity formed in the rod of the push-button.
